CASEMENT WINDOW OPERATOR

2 Sheets=Sheet 2

UNITED STATES PATENT OFFICE.

ROLAND B. WORTHINGTON, OF MIAMI, FLORIDA, ASSIGNOR TO MIAMI MANUFACTURING COMPANY, OF MIAMI, FLORIDA, A CORPORATION OF FLORIDA.

CASEMENT-WINDOW OPERATOR.

Application filed December 26, 1922. Serial No. 609,047.

To all whom it may concern:

Be it known that I, ROLAND B. WORTHINGTON, a citizen of the United States, residing at Miami, in the county of Dade and State of Florida, have invented certain new and useful Improvements in Casement-Window Operators; and I do declare the following to be a full, clear, and exact description of the invention, such as will enable others skilled in the art to which it appertains to make and use the same.

My invention relates to casement window operating and locking devices, and particularly those which operate through or beneath the window screens.

In one form of casement window operators of the type employing an arm pivoted to the swinging window and passing slidably through a casing which is received in a notch in the lower end of the usual window screen, the upper section of the casing is rotatably mounted to turn with the window operating arm as the latter is moved inwardly or outwardly, but it often happens that swelling of the screen will bind the walls of its notch against the rotary casing section and will therefore interfere with proper operation of the device. Furthermore, the casings to which I refer, have occupied a great deal of space upon the window sill and have extended both inwardly and outwardly from the screen, which is not only unsightly but often objectionable when the screen is very close to the window sash.

It is one of the objects of the present invention to provide a device which will be free from the above mentioned objections, will be simple and inexpensive to manufacture, will be strong and durable, and will be exceptionally easy to apply to practically all kinds of casement windows.

In carrying out the above ends, a relatively long and narrow casing is secured horizontally upon the window sill to be snugly received in a rectangular notch in the lower end of the screen, opposite sides of this casing being provided with slots through which the window operating arm extends to be engaged by arm-holding means within the casing. The slots are of such length as to permit the necessary horizontal swinging of the window operating arm, yet the entrance of insects through

these slots is prevented by a novel arrangement of parts.

With the foregoing in view, the invention resides in the novel subject matter herein-after described and claimed, the description being supplemented by the accompanying drawings.

Figure 1 is a horizontal sectional view showing the application of my invention to a screened casement window, the window being closed.

Figure 2 is a duplicate of Fig. 1 with the exception that it discloses the window held in an open position.

Figure 3 is an enlarged top plan view of the casing and a portion of the arm which passes therethrough.

Figure 4 is a horizontal sectional view through the casing showing the internal parts thereof in elevation.

Figure 5 is a duplicate of Fig. 4 but disclosing a different relation of parts.

Figure 6 is a longitudinal sectional view as indicated by line 6—6 of Fig. 3.

Figure 7 is a vertical transverse sectional view on line 7—7 of Fig. 6.

Figure 8 is a detail sectional view as indicated by line 8—8 of Fig. 3.

Figure 9 is a perspective view of the barrier plate which prevents insects from passing through a portion of the casing.

Figure 10 is a perspective view of the slide which in the present embodiment of the invention, prevents insects from entering through the channel of the operating arm.

In the drawings above briefly described, the numeral 1 designates a casement window, 2 has reference to the window frame having the usual sill 3, and 4 indicates an appropriate sliding or swinging screen spaced inwardly from the window.

An operating arm 5 which is preferably of channel form, is suitably pivoted at 6 to a bracket secured to the window 1 and while its outer portion is preferably curved, its inner end will in most instances be straight to lie above the sill 3 when the window is closed as shown in Fig. 1. This inner end of the arm 5 may be provided with any desired form of operating knob 7. One edge of the arm 5 is formed with a plurality of notches 8 which are instrumental in holding the window in a number

of positions and it will be seen by reference to Fig. 1 that one of these notches may co-act with a stud 9 suitably attached to the window sill 3, for the purpose of holding the window closed. When applying the invention, the stud 9 may be located to co-act with the arm 5 for locking the window shut, regardless of whether said arm is otherwise held by the means yet to be described.

A relatively long and narrow horizontal casing 10 is secured to the window sill 3 and located within a notch 11 which may be easily formed in the lower end of a swinging screen or in a notch in a fixed bar beneath a swinging screen. The sides of this casing have longitudinal slots 12 near one end through which the arm 5 passes and the sides are preferably disposed in the planes of the side faces of the screen frame so that the casing will not project laterally beyond the same. Within the casing 10, I provide a suitable stop which is preferably in the form of an upright post 13 for co-action with the notches 8 to hold the window in different adjusted positions. The edge of the arm 5 opposite the notches 8, is engaged by a roller 14 on the end of a plunger 15 which is longitudinally movable in the casing 10, an appropriate coil spring 16 being employed to force said plunger in a direction to effect engagement of an arm notch 8 with the post 13, when the arm is adjusted to any predetermined position.

In the construction shown, the casing 10 is provided with a rectangular base plate 17 having openings 18 in its ends to receive attaching screws 19, this plate and the parts 13, 14, 15 and 16, being entirely covered by the top and vertical sides of the casing as shown. The base plate 17 preferably carries all parts of the device except the arm 5. In the present showing, the post 13 is secured to the plate 17 as indicated at 20 in Fig. 6, the body portion of the plunger 15 rests on said plate and is held in proper position thereon by an arched bearing 21 secured to said plate, and another bearing 22 rises from this same plate to guide a stem 23 which is surrounded by the spring 16 and forms a part of the plunger. The casing may well be secured at one end to the bearing 22 and at its other end to the post 13, for which purpose I have shown screws 24. The casing top is formed with a pair of openings 25 giving access to the screw holes 18 and it will thus be seen that the casing and parts contained therein may be sold in an assembled condition and need not be disassembled to any extent whatever when applying to the window sill, it being simply necessary to drive the screws 19 by passing them and a screw driver through the openings 25.

In order to permit the necessary horizon-

tal angling of the operating arm 5, the slots 12 are rather long. Provision is made however to prevent insects from entering the building through these slots. In the present showing, I have illustrated a longitudinally disposed barrier wall 26 rising from the base plate 17 and extending from the post 13 toward the adjacent end of the casing 10, the end of the wall which abuts said post, being preferably thinned as indicated at 27, 75 to interfere in no manner with proper engagement of the notches 8 with said post. This prevents insects from seeing light and entering at the notched edge of the arm 5 and the plunger 15 performs a similar function 80 at the opposite edge of said arm 5. The insects are prevented from entering through the channel of the operating arm 5, by means of a flange 28 which depends from a horizontal slide plate 29, this plate being 85 positioned over the plunger 15 and connected therewith by any suitable means, such as an upstanding pin 30 on the plunger received in an opening 31 in the plate. This plate 29 preferably rests slidably upon the 90 bearing 20 and upon the wall 26 and may well be formed with a slot 32 receiving the upper end of the post 13.

While such an arrangement has not been shown, it would of course be possible to provide the sliding plate 29 with some form of depending flange which would perform the same function as the barrier wall 26.

By providing the construction shown or a substantial equivalent thereof, a device 100 is provided which may be easily and inexpensively manufactured, which may be applied with ease by unskilled labor, and may be very conveniently and easily operated. It may be explained that as the distance between the window and the screen is not always uniform, it would not be advisable to have the arm 5 engage the post 13 for locking the window closed, as this would necessitate an accurate positioning of the casing 110 10 upon the window sill and would not in all cases permit the disposition of this casing in a notch in the screen. Hence, I provide the additional fastening stud 9 which may be secured to the sill at any desired 115 point, regardless of where the casing is located. This stud, it will be noted, co-acts with one of the notches 8 so that it is unnecessary to provide an additional notch or to recess the opposite edge of the arm 5 which is thus left smooth for free sliding engagement with the antifriction roller 14.

As excellent results have been obtained from the details disclosed, they are preferably followed. However, within the scope 125 of the invention as claimed, numerous minor changes may be made.

I claim:

1. A casement window operator comprising a relatively long and narrow horizon-

- tally disposed casing adapted to be secured upon a window sill within a rectangular notch in the lower end of a window screen, opposite sides of the casing having slots, a 5 window operating arm extending through said slots, and a spring-pressed plunger disposed longitudinally in said casing and engaging said arm to effect holding of the latter in adjusted position.
- 10 2. A casement window operator comprising a relatively long and narrow horizontally disposed casing adapted to be secured upon a window sill within a rectangular notch in the lower end of a window screen, opposite 15 sides of the casing having slots adjacent one end of said casing, a stop in said one end of the casing, a window operating arm passing through said slots and having notches to engage said stop, and a spring-pressed 20 plunger disposed longitudinally in the casing and bearing against said arm to force the same toward said stop.
3. A casement window operator comprising a horizontally elongated rectangular base plate having screw holes in its ends, a fixed post rising from said plate near one end thereof, bearings on the upper side of said plate between said post and the other end of said plate, a spring-pressed plunger 25 mounted in said bearings and movable toward said post under the influence of the spring, a window operating arm received between said plunger and said post and notched to engage the latter under the action 30 of said plunger, and an elongated casing fitting over said base plate, said post, said plunger and said arm and secured with respect thereto, said casing having slots receiving said arm and being formed with 35 openings in its top giving access to said screw holes.
4. A casement window operator comprising a horizontally elongated casing adapted to be secured upon a window sill, opposite 40 sides of said casing having longitudinal slots, a post within the casing near one end of said slots, a window operating arm passing through said slots and notched in one edge to engage said post, a spring-pressed 45 plunger in the casing engaging the edge of the arm remote from said post, and a longitudinal barrier wall extending from said post toward the adjacent end of the casing, 50 said barrier wall and plunger preventing in-
- sects from passing through the casing at opposite edges of the arm.
5. A casement window operator comprising a horizontally elongated casing adapted to be attached to a window sill and having slots in its opposite sides, a window operating arm passing through said slots, holding means for said arm including a spring-pressed plunger in the casing and a slide 55 connected to said plunger, said slide having a portion operative to bar insects against 60 a portion of the casing.
6. A casement window operator comprising a horizontally elongated casing adapted to be attached to a window sill and having slots in its opposite sides, a window operating 65 arm of channeled form passing through said slots, holding means for said arm including a spring pressed plunger in the casing, and a slide over said plunger connected with the latter, said slide having a depending flange 70 extending across the channel of said arm.
7. A casement window operator comprising a guide adapted to be secured to a window sill within a notch in a screen, a window operating arm passing through 75 said guide and formed in one edge with notches to engage the same for holding the window in open positions, said arm being curved to lie over the sill when the window is closed, and a detent adapted to be secured 80 to the sill for reception in one of said arm notches for holding the window closed.
8. A casement window operator comprising a relatively long and narrow stationary 85 rectangular casing adapted to be fixed upon a window sill within a rectangular notch in the lower portion of a window screen frame, the opposite side walls of the casing having 90 slots, and being flat and parallel to lie in the planes of the inner and outer faces of the 95 screen frame, a longitudinally curved one-piece rigid window operating arm extending through said slots and having notches in one edge, a bracket for rigid attachment to a window pivoted directly on one end of the 100 arm, a stop within the casing for engagement by the notches in the arm, and spring pressed means within the casing engaging the unnotched edge of the arm to maintain the latter in engagement with the stop.
- In testimony whereof I have hereunto 105 affixed my signature.
- ROLAND B. WORTHINGTON.
